CLAIM

The ornamental design for a display screen with an animated graphical user interface, as shown and described.

DESCRIPTION

FIG. 1 is a front view of a first image in a sequence of a display screen with an animated graphical user interface, showing a first embodiment of our new design;

FIG. 2 is a second image of the first embodiment;

FIG. 3 is a third image of the first embodiment;

FIG. 4 is a fourth image of the first embodiment;

FIG. 5 is a fifth image of the first embodiment;

FIG. 6 is a front view of a first image in a sequence of a display screen with an animated graphical user interface, showing a second embodiment of our new design;

FIG. 7 is a second image of the second embodiment;

FIG. 8 is a third image of the second embodiment;

FIG. 9 is a fourth image of the second embodiment; and,

FIG. 10 is a fifth image of the second embodiment.

The appearance of the animated graphical user interface sequentially transitions between the images shown in FIGS. 1-5, and 6-10. The process or period in which one image transitions to another image forms no part of the claimed design.

The top broken line ovals show portions of the display device and all other broken lines show portions of the graphical user interface. All broken lines form no part of the claimed design.

1 Claim, 10 Drawing Sheets
